Ezra B. Smith

BY *E. W. Marshall*
ATTORNEY

UNITED STATES PATENT OFFICE.

EZRA B. SMITH, OF RAVENSWOOD, ILLINOIS, ASSIGNOR TO JOHN EDWARD OGDEN,
OF MOUNTAINVILLE, NEW YORK.

CONTROL MECHANISM FOR DOORS.

Application filed December 11, 1922. Serial No. 606,277.

This invention relates to doors and particularly to doors of the type used in elevator hatchways and like structures.

As is well known it is very important that all hatchway or fire doors be closed in case of fire. It is also desirable that means be provided for holding or latching the doors open under predetermined conditions such, for instance, as when an elevator car is opposite a landing.

This invention has for its salient object to provide automatically operable heat responsive means for releasing open hatchway doors in case of fire.

Another object of the invention is to provide an automatically operable heat responsive alarm device.

Another object of the invention is to provide means, in conjunction with mechanism for latching doors in open position, for releasing said mechanism in case of a dangerous rise in temperature.

Further objects of the invention will appear from the following description taken in connection with the drawings which form a part of this application and in which,

Fig. 1 is a sectional elevation of an elevator hatchway showing a plurality of hatchway doors.

Fig. 2 is a sectional elevation of one side of the hatchway shown in Fig. 1.

Fig. 3 is an enlarged elevation showing the mechanism for latching doors open and the automatically operable heat responsive releasing device for the latching mechanism and also the alarm device operable in conjunction therewith.

Fig. 4 is a transverse sectional elevation taken substantially on line 4-4 of Fig. 3.

Fig. 5 is a transverse sectional elevation taken substantially on line 5-5 of Fig. 3.

Fig. 6 is a transverse sectional elevation taken substantially on line 6-6 of Fig. 3.

The invention briefly described comprises a heat responsive means operable in conjunction with mechanism for latching doors in open position for releasing said latching mechanism whereby the doors will be automatically closed in case of a dangerous rise in temperature. The invention also includes an alarm device so constructed and arranged that an alarm will be given under the con-

ditions mentioned and at the time the doors are closed.

Referring to the drawings there is shown in Fig. 1 a portion of an elevator hatchway 10 having a plurality of sets of doors A and B located at different floor levels 12 and 13.

In the particular form of the invention shown an upper section 14 and a lower section 15 is provided for each door opening, these sections being movable toward each other to closed position and being movable away from each other to open position. A latch 16 is carried by one of the sections, 14, and the other section 15 has a latch engaging member 17. Doors A are shown as closed and doors B are shown as open. As the doors are moved to closed position the latch 16 is automatically swung into latching position.

The hatchway doors may be counterbalanced in any suitable manner and one satisfactory arrangement consists in making the upper section 14 heavier than the lower section 15 so that when the sections are released after having been latched in open position they will automatically close. The two doors of each set are connected by a cable 18 secured to the lower edge of the upper section as shown at 19 and to a bracket secured to the upper edge of the lower section as shown at 20. The intermediate portion of the cable 18 passes over a sheave 21 mounted in the hatchway on a fixed support.

It is desirable that only one pair of doors or door sections be opened at one time and in Fig. 1 the sections B are shown as open and the sections A as closed. It will be obvious that the upper section B will prevent the lower section of the doors located above the landing 12 from opening and the lower section B will prevent the upper door section at the landing below landing 13 from opening, as all of the sections are guided in the same vertical plane. Mechanism is provided for each set of doors for latching the doors in open position and particular attention is directed to Fig. 3 wherein the details of this construction are shown. The latching mechanism comprises a disc 30 eccentrically pivoted at 31 to a fixed support 32 mounted in the hatchway. The disc 30 has secured thereto an arm 33 and a latch 34

is pivotally secured at 35 to the upper end of the arm 33. The latch is normally swung to the position shown in Fig. 3 by a spring 36 and is limited in its movement in a clockwise direction by a stop lug 37 engageable with one edge of the arm 33. The latch 34 is adapted to engage a bracket 38 projecting laterally from one edge of the lower door section 15 and the descending movement of this section is limited by a stop lug 39 secured in the hatchway and disposed in the path of the bracket 38. A slight clearance is preferably provided between the latching position of the bracket 38 and the lug 39.

10 The normal or inoperative position of the latching mechanism is illustrated in Fig. 1 in connection with the mechanism adjacent the floor level 12. From the showing referred to it will be seen that the arm 33 is inclined away from the doors. This is due to the eccentric pivoting of the disc 30 and to the location of the center of gravity in such a manner that the disc will be swung in this inclined position when freely movable about its pivot. Means has been provided however for moving the latching mechanism to operative position as the lower section of the doors is moved to its open position. This engagement of the strip 40 on the lower door section with the roller 41 on the disc 30 will swing the disc 30 about its pivot 31 to the position shown in Fig. 3 wherein the latch 34 is engageable with the bracket 38 carried by the section 15.

20 25 30 35 Means has been provided for automatically releasing the latching mechanism when the elevator car leaves the floor level either ascending or descending. This means comprises a pair of rollers or studs 42 projecting laterally from one edge of the elevator car and disposed in the path of the pivot pin 35 of the latch 34 when the latch is located in latching position as shown in Fig. 3. Assuming that the doors opposite an elevator landing have been opened by the car operator, and latched open, as soon as the car is started in either direction one of the rollers or studs 42 will engage the pin 35 thereby swinging the arm 33 and disc 30 about the disc pivot 31 in a clockwise direction, thus releasing the latch 34 from the bracket 38 and permitting the doors to close.

40 45 50 55 60 65 It will be evident from the description in the preceding paragraph that when the rollers or studs 42 release the latch of an open door the latch remains in retracted position as the spring 40 is moved out of contact with the pin 41 by the door movement. In this manner noise and wear and tear on the latch is avoided. Furthermore, the rollers 42 do not contact with the latch as the elevator platform passes closed doors and for this reason useless movement of the latch is prevented and noise and wear and tear are eliminated. In other words, the latch moves

70 to operative position only when it is needed to hold one of the hatchway doors open. At all other times the latch is in inoperative position and is disposed out of the path of movement of the rollers or studs 42.

75 The heat responsive means for automatically unlatching the latching mechanism will now be described. This means consists primarily of a weight 50 suspended by a chain 51 from a fusible link 52, the opposite end of the link being connected by a chain 53 to a fixed support 54. The downward movement of the weight 50 is limited by a stop pin 56 disposed in an elongated slot 57 formed in the weight.

80 The weight 50 acts to release the latching mechanism through the agency of a lug 58 extending laterally from the weight and engageable with an arm 59 secured to the disc 30 and disposed in the path of the lug 58.

85 The swinging movement of the disc 30 about its pivot 31 is limited by a headed stud 60 secured to the fixed support 32 and disposed in a notch 61 formed in the periphery of the disc.

90 The heat responsive releasing means operates as follows. When a dangerous rise in temperature takes place the fusible link will be melted thereby dropping the weight 50. As the weight drops the lug 58 carried thereby will engage the arm 59 carried by the disc 30, thus swinging the disc about its pivot 31 in a clockwise direction and releasing the latch 34 from the bracket 38 carried by the door section 15.

95 An alarm device has been provided for sounding an alarm when the dangerous rise in temperature takes place and the releasing means for the latching mechanism becomes operative. This device in the particular embodiment of the invention shown consists of an alarm circuit 70 including a pair of contact terminals 71 and 72. The terminal 71 is preferably formed of resilient material and is normally held in raised position and out of engagement with the terminal 72 by means of the weight 50 the upper end of which engages a downwardly extending portion 73 of the terminal 71. When the weight 50 is dropped after the fusible link 52 has been melted the terminal 71 will contact with the terminal 72 thereby closing the circuit 70 and sounding a bell 74 or some other suitable alarm device.

100 105 110 115 120 125 From the foregoing specification it will be seen that simple, practical and effective means has been provided for insuring the closing of hatchway doors in the event of a dangerous rise in temperature in the hatchway. Furthermore provision has been made for alarming the operator or caretaker when such an event takes place.

130 Although one specific embodiment of the invention has been particularly shown and

described, it will be understood that the invention is capable of modification and that changes in the construction and in the arrangement of the various cooperating parts 5 may be made without departing from the spirit or scope of the invention as expressed in the following claims.

What I claim is:—

1. In combination, a movable hatchway door biased to close, mechanism, normally disconnected from the door and disposed in unlatching position, for latching the door in open position, means engageable with said latching mechanism and operable upon movement of the door to open position to move said mechanism from its unlatching position to its latching position when the door is open and means controlled by a heat controlled element for moving said latching mechanism 20 to unlatching position.

2. In combination, a slidable hatchway door biased to close, mechanism, normally disposed in unlatching position, for latching the door in open position, means engageable 25 with said latching mechanism and operable upon movement of the door to open position to move said mechanism from its unlatching position to its latching position when the door is open and gravity actuated means controlled by a heat controlled element for moving said latching mechanism to unlatching 30 position.

3. In combination, a movable hatchway door biased to close, mechanism, normally disposed in unlatching position and out of 35 engagement with the door, for latching the door in open position, means engageable with said latching mechanism and operable upon movement of the door to open position 40 to move said mechanism from its unlatching position to its latching position when the door is open and means controlled by a fusible link for moving said latching mechanism to unlatching position.

4. In combination, a movable hatchway door biased to close, mechanism, normally disposed in unlatching position, for latching the door in open position, means engageable 45 with said latching mechanism and operable upon movement of the door to open position to move said mechanism from its unlatching position to its latching position when the door is open and means including a weight suspended by a fusible link and engageable 50 with the latching mechanism for releasing said mechanism.

5. In combination, a movable hatchway door biased to close, pivoted latching mechanism, normally disposed in unlatching position, for latching the door in open position, means engageable with said latching mecha-

nism and operable upon movement of the door to open position to move said mechanism from its unlatching position to its latching position when the door is open and 65 means including a weight suspended by a fusible link and engageable with the latching mechanism to swing said mechanism on its pivot and release said mechanism from latching position.

6. In combination, a movable door biased to close, latching mechanism, normally disposed in unlatching position, and adapted to latch the door in open position, means movable with the door and engageable with 70 said latching mechanism to move said mechanism to latching position and heat controlled means including a weight for releasing said latching mechanism from the door, 75 said latching mechanism having a portion 80 disposed in the path of movement of said weight and engageable thereby.

7. In combination, a movable door biased to close, latching mechanism arranged to hold the door in open position, normally disposed in inoperative position, means carried 85 by the door for moving said mechanism to operative latching position and heat responsive means including a weight and means on the latching mechanism engageable thereby 90 for moving said latching mechanism out of latching position.

8. In combination, an elevator, a movable hatchway door biased to close, latching mechanism arranged to hold the door in open 95 position normally disposed in inoperative position, means carried by the door for moving said mechanism to operative latching position, means actuated by the movement of the elevator car away from an open hatchway door opening for releasing the latching mechanism, and heat responsive means including a weight for moving said latching mechanism out of latching position.

9. In combination, an elevator, a movable 105 hatchway door biased to close, latching mechanism arranged to hold the door in open position normally disposed in inoperative position, means carried by the door for moving said mechanism to operative latching 110 position, means actuated by the movement of the elevator car away from an open hatchway door opening for releasing the latching mechanism, and heat responsive means including a weight and means on the 115 latching mechanism engageable thereby for moving said latching mechanism out of latching position.

In witness whereof, I have hereunto set my hand this 7th day of Dec., 1922.

EZRA B. SMITH.
